US0D1114179S

(12) **United States Design Patent** (10) **Patent No.:** **US D1,114,179 S**
(45) **Date of Patent:** **** Feb. 17, 2026**

(54) **FREESTANDING BATHTUB FAUCET**

(71) Applicant: **HANSGROHE SE**, Schiltach (DE)

(72) Inventor: **Antonio Citterio**, Milan (IT)

(73) Assignee: **HANSGROHE SE**, Schiltach (DE)

(**) Term: **15 Years**

(21) Appl. No.: **29/930,803**

(22) Filed: **Mar. 2, 2024**

(30) **Foreign Application Priority Data**

Sep. 4, 2023 (EM) 015032971-0005

(51) **LOC (15) Cl.** **23-01**

(52) **U.S. Cl.**

USPC **D23/238**

(58) **Field of Classification Search**

USPC D23/238, 239, 242, 241

CPC E03C 2201/30; E03C 1/01; B05B 12/002

See application file for complete search history.

Primary Examiner — Gino Colan

(74) *Attorney, Agent, or Firm* — Lora J. Graentzdoerffer

(57) **CLAIM**

The ornamental design for a freestanding bathtub faucet as shown and described.

DESCRIPTION

FIG. 1 is a perspective view of a freestanding bathtub faucet showing my design;

FIG. 2 is a front elevational view;

FIG. 3 is a rear elevational view;

FIG. 4 is a side elevational view;

FIG. 5 is a side elevational view;

FIG. 6 is a top plan view; and,

FIG. 7 is a bottom plan view.

The broken line disclosures in the view represents portions of a freestanding bathtub faucet in which the claimed design is embodied, but which forms no part of the claimed design.

1 Claim, 7 Drawing Sheets
